Marion Hawick, Attorney

United States Patent Office.

WILLIAM H. SMITH, OF NEWPORT, RHODE ISLAND.

Letters Patent No. 97,716, dated December 7, 1869.

IMPROVED BOOT AND SHOE-CLEANER.

The Schedule referred to in these Letters Patent and making part of the same.

To all whom it may concern:

Be it known that I, WILLIAM H. SMITH, of Newport, in the county of Newport, and State of Rhode Island, have invented a new and improved Boot and Shoe-Cleaner; and I do hereby declare that the following is a full, clear, and exact description thereof, reference being had to the accompanying drawings, making part of this specification, in which—

Figure 1 is a perspective view of the improved boot and shoe-cleaner.

Figure 2 is a top view of the cleaner, with a portion of one of the rotary brush-shields broken away.

Similar letters of reference indicate corresponding parts in both figures.

The nature of my invention consists—

First, in combining, with a rotary corrugated drum, two upright rotary brush-drums, in such manner, that in the act of drawing the foot over the corrugated drum, this drum will turn, and at the same time, give rotary motion to the upright brushes, which will clean the sides of the boot or shoe, as will be hereinafter explained.

Second, in combining, with said rotary drum and rotary brushes, a scraper and a fixed brush, which will clean the bottom of a boot while the rotary brushes clean the sides thereof, as will be hereinafter explained.

To enable others skilled in the art to understand my invention, I will describe its construction and operation.

In the accompanying drawings—

A represents the base-plate of the chamber, which is flat on top, and preferably made of cast-metal.

B represents a rotary cylinder, which has its periphery corrugated, serrated, or roughened, in any suitable manner, and is supported at both ends by short forked standards b, rising perpendicular from and secured rigidly to the base-plate A.

On the extremities of the shaft of cylinder B, bevelled-spur wheels g, g are keyed, which engage with corresponding wheels g', on vertical shafts e.

The shafts e have their bearings in the offsets of standards b, and carry brush-drums E, arranged in such relation to the ends of the cylinder B, that when a person draws his foot across the latter, and rotates it, the brushes E E will be rotated, and will clean the sides of the boot.

On one side of the cylinder B, and secured fast to the bed A, is a convex brush, D, and on the opposite side of said cylinder is a scraper-plate, O, which is also secured fast to the bed A.

It will be seen that during the act of drawing the foot over cylinder B, and brushing the side or sides of the boot, the scraper G and brush D will clean the bottom of the boot.

I am aware that laterally-movable elastic or yielding brushes, for cleaning the sides of a boot, have been combined with brushes and scrapers for cleaning the bottom of a boot, and I lay no claim to such combination; nor do I claim, broadly, the use of cylindrical rotary brushes. I have combined a corrugated or roughened cylinder or driver with rotary brushes, in such manner that the act of moving the foot between the rotary brushes upon the said driver, causes the brushes to rotate.

Having described my invention,

What I claim as new, and desire to secure by Letters Patent, is—

1. The upright rotary brushes, geared and combined with the cylindrical corrugated driver B, as and for the purposes described.

2. The scraper O, and brush D, in combination with brushes E, and their driving-cylinder B, as described.

WM. H. SMITH.
